CEILING AIR DEFLECTOR FRAME

Ward Bledsoe, 3548 Maricopa Way,
Las Vegas, Nev. 89109

Filed Dec. 2, 1971, Ser. No. 204,395

Term of patent 14 years

Int. Cl. D23—04

U.S. Cl. D23—112

FIG. 1

FIG. 2

FIG. 3

FIG. 1 is a front elevational view of a ceiling air deflector frame showing my new design;

FIG. 2 is a cross-sectional view taken through the middle of FIG. 1; and

FIG. 3 is a front perspective view thereof. The rear of the frame is formed with ridges and grooves or indentations as illustrated in FIG. 2 conforming to the front surface shape of the frame as shown.

I claim:

The ornamental design for a ceiling air deflector frame, as shown and described.
